FOREIGN PATENT DOCUMENTS

AU 2019201306 B1 5/2020

Primary Examiner — Alison M Ofstun

(74) *Attorney, Agent, or Firm* — Thomas M. Joseph, Esq

(57) **CLAIM**

The ornamental design for a shaving apparatus, as shown and described.

DESCRIPTION

FIG. 1 is a perspective view showing my new design;

FIG. 2 is a top view thereof;

FIG. 3 is a right side view thereof;

FIG. 4 is a left side view thereof;

FIG. 5 is a front view thereof;

FIG. 6 is a rear view thereof; and,

FIG. 7 is a bottom view thereof.

Any material that is shown in dashed lines is for clarity only, and forms no part of the invented design.

In the drawings, the broken lines illustrate portions of the article which form no part of the claimed design.

1 Claim, 4 Drawing Sheets
